UNITED STATES PATENT OFFICE

2,479,369

CIGARETTE AND CIGAR TRAY CLASP

George J. Kamphaus, Indianapolis, Ind.

Application October 13, 1947, Serial No. 779,438

11 Claims. (Cl. 24—252)

1

This invention relates to a cigar or cigarette clamp type support.

The chief object of the present invention is, in addition to retaining all the advantages of prior art devices, to provide for one-hand operation of the clamp device and by article (cigar and cigarette) contact.

The chief feature of the present invention resides in providing a floating jaw and associating therewith a pivoted jaw, the latter being pivoted on the former and fulcruming upon a base by virtue of which the former is supported by the base.

Essentially the operative association is of over-center or toggle type.

Other objects and features of the invention will be set forth more fully hereinafter.

The full nature of the invention will be understood from the accompanying drawings and the following description and claims:

In the drawings Fig. 1 is a top plan view of an ash tray provided with a conventionally grooved rest, a vertical disposed clamp and a horizontally disposed clamp, the clamps each embodying the present invention.

Fig. 2 is an enlarged side elevation of the vertically disposed clamp device, parts of the tray being shown in section, the article being indicated by dotted lines and with parts shown in initial position to effect clamping.

Fig. 3 is a similar view of the same parts with the article in clamped position.

Fig. 4 is an elevational view of the clamp device and is taken at right angles to Figs. 2 and 3.

In Fig. 1 of the drawings 10 indicates the bowl of an ash tray having rim 11 and to which may be secured a U-shaped support 12, a vertically disposed embodiment of the invention 13 and an overhanging arm 15 which may also support a horizontally disposed embodiment of the invention 16.

Reference will now be had to Figs. 2, 3 and 4. The rim 11 is slotted as at 17 and apertured as at 18. A bolt 19, or rivet seated in the latter rigidly secures arm 20 to the rim. This arm is integral with a U-shaped base member having mid-portion 21 and side walls 22. The latter is cut away at 23 to provide tongue 24 disposed between the walls 22. Portions 21, 22 and 24 serve as a spring trap and retainer for a coil spring 25, hereinafter the term base designates broadly member 20, portion 21 and sides 22.

The upper ends of side walls 22 are notched as at 26 to form a seat upon which rests the tail portion 27 of a clamping jaw 28. The lower ends

of the side walls 22 terminate in tongues 29. These seat in slots 30 in the bottom 31 of the floating jaw structure to be described.

This structure comprises a generally U-shaped member having mid-portion 32 and side walls 33. The bottom 31 is an extension of mid-portion 32 and includes an upturned end 34. The spring 25, which at its upper end bears upon tongue 24 and is retained by lip 24 thereof, at its lower end bears upon the bottom portion 31 between slots 30 of the floating jaw structure.

The floating structure terminates in jaw portion 35 and the upper inturned ends 36 of side walls 33 form an article rest as shown. The jaw 28 includes spaced ears 37 and pin 38 or the like is anchored in and to the side walls 33.

The resulting structure is such that while spring 25 normally tends to draw down the floating jaw structure, same is limited by the pivoted jaw bearing upon seats 26 for that jaw is pivoted to the floating jaw. The arrangement is further characterized by the fact that when the pivoted jaw is tilted counterclockwise, compare Figs. 3 and 2, the entire structure similarly tilts and the jaws open. Such movement is limited by jaw 28 contacting the adjacent end of rim slot 17.

When article clamping is desired, it is disposed between the open jaws and jaw 35 is moved clockwise from Fig. 2 to Fig. 3 position, which effects article clamping. This movement is limited by jaw 32—35 engaging the opposite end of rim slot 17. Note further that as the floating jaw structure is so moved pivot 38 elevates since the pivoted jaw 28 fulcrums at seats 26.

Thus the operation is one hand operable for clamping and releasing. The action essentially is of toggle or over-center type.

In the lateral arm supported form designated by numeral 16 in Fig. 1 the jaw movements are up and down to effect release and clamping respectively.

While the invention has been described in great detail in the foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a holder for cigars, cigarettes and similar articles having a pair of confronting article clamping and releasing jaws, the combination of

a pivotal connection between said jaws, each having an extension extending oppositely from the jaw beyond the pivotal connection, a seat upon which one jaw extension fulcrums, a base operatively associated with the other jaw, spring means operatively interposed between the seat and said other jaw, and stops limiting the extent of oscillatory movement of the jaws.

2. A holder as defined by claim 1 wherein the spring means is of compression type and the pivotal connection between jaws passes over-center with respect to said seat in the oscillatory movement of said jaws.

3. A holder as defined by claim 2 wherein the said other jaw extension is substantially U-shaped in cross-section and the base is substantially U-shaped in cross-section, the said sectioned extension and base having confronting interfitting association with the spring means nested therebetween.

4. A holder as defined by claim 1 wherein side portions of the base incorporate said seat.

5. A holder as defined by claim 4 wherein the mid-portion of the base includes a tongue formed therefrom providing a bearing for one end of the spring means.

6. A holder as defined by claim 1 wherein the said other jaw extension is substantially U-shaped in cross-section and the base is substantially U-shaped in cross-section, the said sectioned extension and base having confronting interfitting association with the spring means nested therebetween.

7. A holder as defined by claim 6 wherein the said other jaw includes an integral article support portion.

8. In a holder for cigars, cigarettes and like articles having a pair of confronting jaws, the combination of a connection therebetween for disposing the jaws in article receiving released position and article clamping position, a constraining medium for yieldingly maintaining the jaws in either of the two positions, and a floating support for one of the jaws, the jaws being article movable to either position.

9. A holder as defined by claim 8 wherein one of the jaws includes an article support portion.

10. A holder as defined by claim 8 wherein the connection is of pivotal character and a fulcrum supports the other jaw.

11. A holder as defined by claim 10 wherein one of the jaws includes an article support portion.

20 GEORGE J. KAMPHAUS.
